Primary Examiner — Mojtaba Tehrani(74) *Attorney, Agent, or Firm* — Raymond Chan(57) **CLAIM**

The ornamental design for a gunstock, as shown and described.

DESCRIPTION

FIG. 1 is a front perspective view of gunstock showing my new design;

FIG. 2 is a front view thereof;

FIG. 3 is a rear view thereof;

FIG. 4 is a left end view thereof;

FIG. 5 is a right end view thereof;

FIG. 6 is a top view thereof;

FIG. 7 is a bottom view thereof; and,

FIG. 8 is a rear perspective view thereof.

The evenly broken line within the drawings depicts unclaimed portion of the gunstock; the dash-dot broken line depicts the boundary of the claimed design. The broken lines form no part of the claimed design.

1 Claim, 6 Drawing Sheets(56)
